UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PUMPING SYSTEM.

Application filed September 10, 1921. Serial No. 499,760.

My invention relates to pneumatic pumps and pumping systems, and particularly to pumps and systems of the "fresh water" type wherein the pump is submerged in the liquid 5 to be pumped such as the water at the foot of the well or other source of supply and is connected to a normally closed distributing system, such as the pipes and fixtures of a dwelling or the like, the operation of 10 the pump being automatically controlled by the opening and closing of the faucets or fixtures. Such systems are also characterized as "faucet controlled" or "closed" systems.

While my invention is particularly useful 15 in faucet controlled systems it is also useful in open pumping.

In recent years single cylinder pumps for use in such systems have been developed and have become popular largely because of 20 the cheapness and simplicity of structure. In systems employing a single cylinder pump an "air spring" or reservoir often termed a steady flow chamber, is employed to provide the flow of water between the 25 strokes of the pump. In carrying out my invention I employ in one form thereof an air spring as the means for equalizing the pressure in the consumption system and for controlling the valve which admits and exhausts motive fluid to and from the pump at each stroke.

Broadly the control of the main air valve for the main pump cylinder is disclosed in my prior applications in which I have shown 35 various methods of control exercised from the auxiliary pumping chamber or steady flow chamber.

In the present invention I control the main air valve preferably in accordance with 40 the direction of flow exhibited by the liquid with respect to the steady flow or auxiliary pumping chamber. The main and auxiliary chambers are connected together and to the distribution system. The main pump chamber is so constructed that it tends to throw 45 or displace a certain quantity of water. After the level in the main pump chamber drops to a certain minimum level the main chamber is shut off from both the steady 50 flow chamber and from the distribution system. When flow from the main chamber ceases this is a manifestation which I employ as a control of means for shifting the main air valve to disconnect the source of

motive fluid and to connect the main pump 55 chamber to exhaust. As the system draws its liquid at this time from the steady flow chamber I employ this flow also as a control in connection with the cessation of flow from the main chamber as governing the 60 air valve as above stated. The auxiliary chamber now supplies the distribution system until a certain low level of liquid is attained in said chamber at which time the main valve is shifted to close the exhaust 65 and admit motive fluid to the main chamber. The main chamber fills during the interval that the auxiliary chamber is supplying the distribution system.

Thus the two chambers alternate in filling and discharging.

All the motive fluid valve mechanism may be put above the liquid in a readily accessible position such as at the head of the well. If desired a motor and relay valve mechanism may be employed in order to avoid wasting a pipeful of air at each stroke.

The pump cannot possibly blow over as the two chambers are each provided with low level check valves that prevent the exit 80 of motive fluid from them.

The valve which controls the admission and exhaust of motive fluid to the pump is located at the head of the well and preferably connected to the auxiliary pumping 85 means. Consequently better attention can be given to the working parts of the pump and valves and in case of repairs required by the motive fluid valve, much less work and difficulty is involved.

I believe that I am the first to provide 90 a stroke responsive means for governing the air valve governed by the direction of flow of fluid.

In order to apprise those skilled in the 95 art how to practice my invention I shall describe a specific embodiment of the same in connection with the accompanying drawings, which form part of the present specification.

Figure 1 is a diagrammatic view of a 100 system embodying my invention, in which the valve at the head of the well directly controls the admission and exhaust of motive fluid to the working cylinder of the pump, by control exercised by the flow of the liquid;

Figure 2 is a similar diagrammatic view

illustrating a modified form of structure employed, in which the valve at the head of the well works through one form of motor and valve for controlling the admission and 5 exhaust of motive fluid to and from the main pump cylinder;

Figure 3 is an enlarged fragmentary cross section with parts broken away showing the modified form of structure illustrated in 10 Figure 2;

Figure 4 is a diagrammatic illustration of a modification in which the valve at the head of the well operates through a liquid column to operate a motor and a relay 15 valve which controls the admission and exhaust of motive fluid to and from the main pump cylinder;

Figure 5 is an enlarged rear elevation of 20 said motor and valve; employed in the modification of Figure 4;

Figure 6 is an enlarged cross sectional view of the same motor and valve taken on line 6—6 of Figure 4;

Figure 7 is a longitudinal sectional view 25 of the main pump cylinder with parts broken away showing the low level check valve;

Figure 8 is a diagrammatic illustration 30 indicating the uppermost position of the motive fluid valve at the head of the well, during the time that the main pump chamber is discharging;

Figure 9 is a similar diagrammatic illustration 35 indicating the intermediate position of the said valve during the time that the motive fluid is exhausting from the pump;

Figure 10 is a similar diagrammatic view 40 illustrating the lowermost position of the said valve when the main pump chamber has refilled and motive fluid is being admitted;

Figure 11 is a longitudinal cross section 45 of the valve section taken on the line 11—11 of Figure 10;

Figure 12 is a fragmentary longitudinal section 50 of the main valve structure as employed in the system illustrated in Figure 1;

Figure 13 is a view similar to Figure 12 55 with the valve in another position.

The main pump cylinder 1 is submerged 60 in the water in the well so that, when the exhaust of the motive fluid occurs or when no pressure is on the pump the water will fill the cylinder by gravity or what is termed submergence pressure.

The system which is shown in Figure 1 65 comprises the main pump cylinder 1, the steady flow chamber or air spring 2 and the tank 3, for compressed air or other motive fluid. In this embodiment the flow of motive fluid to the pump cylinder is controlled by the valve mechanism 4 disposed adjacent to and in communication with the lower part of the tank 5. The steady flow chamber 65 may be termed an auxiliary pumping device

because of the function which it performs as will be described later. The valve mechanism 4 controls the operation of the ports governing the flow of motive fluid to and from the pump chamber 1. 70

Motive fluid such as compressed air may be furnished from any suitable source, as the tank 3. The tank 3 may be suitably recharged periodically by means of the compressor 6 operated by a suitable motor 7. 75 Means may be provided for automatically recharging the tank 3 when the pressure head therein falls below a predetermined point. The compressed air is supplied to the main pumping chamber in this case at 80 full tank pressure as indicated by gauge 9 by way of pipe 8, valve mechanism 4 and pipe 10. If desired a reducing valve may be placed in the pipe 8. The main pump cylinder 1 is provided with the water discharge pipe 11 which is connected to the auxiliary pumping chamber or air spring 2 at the head of the well, which air spring 85 provides the flow of water through the pipe 12 and the faucets during the intervals between strokes of the main pumping cylinder 1. 90

The pipe 12 leads to a distribution system such as that of a residence or the like. Opening of the faucets permits the discharge 95 of water through the pipes 12 or 11 and out the faucets. As hereinbefore pointed out, the auxiliary pumping chamber or air spring 2 consists of a tank of suitable capacity, the upper part of which is filled with compressed air, as by means of the pipe 13, valve 14 and gauge 15, which connect to the compressor tank 3. The valve 14 is employed to admit sufficient compressed air to the top of the air spring 2 to cause proper operation 100 of the air spring. If desired, a reducing valve 16 for automatically admitting air to the tank may be employed. The pressure applied to the main chamber 1 is great enough to raise the water from the well to 105 the highest point in the system and provide at such highest point a satisfactory pressure, plus the friction head of the liquid flowing in the pipes. A pressure reducing valve 110 may also be employed in pipe 8. The pressure in the tank 5 is less than that applied to the main chamber 1 so that the water may be driven from the well into the auxiliary chamber or tank 5 as will be described later. The air spring operates as an auxiliary 115 pumping device to the extent of providing a satisfactory discharge pressure during the intervals or gaps between the successive strokes of the main pump chamber 1.

The auxiliary pumping chamber 5 is of 120 such a size with respect to the main chamber 1 that it will supply a satisfactory flow for a time interval great enough to permit of filling of the main chamber when the system is operating at its rated capacity. 125

The pump 1 comprises a head member 20 and a foot member 21 having between them a barrel 22 which may be a piece of tubing. The head member 20 contains a 5 passageway 23 which communicates at the upper end with the water discharge pipe and communicates at the lower end with the axial pipe 24 through which the water is discharged from the barrel 22. At the lower 10 end of the pipe 24 a valve casing 26 is secured, this valve casing being in turn connected to the foot member 21 by means of a central bolt 25. The valve casing 26 contains a valve member 27 which serves as a 15 check valve for the pipe 24 and the pipe 11. Passageways 27' in the valve casing 26 communicate with the lower end of the pump barrel 22. The foot member 21 comprises a foot valve 28 controlling the annular passage 29, communicating with the outside of the pump cylinder through the conical screen 30 which is held in place by the central bolt 25.

The valve casing 26 has a head member 31 joined at its periphery to the barrel by means of the packing 32 and the riveted annular ring 33, and which head member 31 has the passages 34. A float valve 35 is adapted to co-operate with the valve passages 34 to close off the same at the end of each stroke of the main pump chamber 1.

The float valve is normally submerged in the water in the barrel 22 and is held against rising by means of the pins 36. As will be 25 hereinafter explained, the float valve member during the filling stroke and the greater part of the discharge stroke periods of the pump is held against the pins 36 and the passageways 34 are permitted to remain 30 open. During the discharge periods of the main chamber the valve 4 permits compressed air to flow by way of the pipe 10 into the upper part of the barrel 22, driving the liquid out by way of valve 27, pipe 24 and pipe 11, until the float valve 35 lowers 35 to its seat and closes the passage 34. This stops further flow from the main chamber and results in reversal of the main air valve as will be described later. Immediately 40 upon exhausting of the motive fluid in the pipe 10 and main chamber 1, by the valve 4, the water entering the lower part of the barrel 22 will cause the float valve 35 to rise and hold against the pins 36. In 45 the case of failure of the water in the well the valve 35 closes off the valve passages 34, preventing any loss of air.

As previously stated, the valve 4 is the 50 means for admitting and exhausting motive fluid to and from the main pump chamber. This valve is governed by a movable member operated by the liquid in accordance with the direction of flow of the liquid. This movable member is subject on one side to 55 pressure from the main chamber and on the

other from the auxiliary chamber. So long as the main chamber is discharging the pressure on the one side of the movable member is in preponderance. As soon as the float valve 35 closes due to the water being 70 lowered in the main chamber, the pressure upon the one side of the movable member drops (due to withdrawal of water via the faucet). This results in a shifting of the main valve to exhaust to permit the main 75 chamber to fill with water. The main chamber should be given ample time to fill. This period is provided for by the auxiliary chamber which provides the discharge pressure at the faucet during the filling period 80 of the main chamber. As soon as the supply of liquid in the auxiliary chamber is exhausted the valve is shifted to the admission position to cause the discharge of liquid from the main chamber. This raises the 85 pressure upon the said one side of the movable element but no shifting of the main valve is thereby occasioned.

In carrying out the above functions I provide an auxiliary valve mechanism in 90 connection with said movable member governing the application of pressures to said movable member. I also provide a low level float valve in the auxiliary chamber which in connection with the auxiliary valve 95 mechanism operates to govern the application of pressure to the other or air spring side of the movable member.

Referring to Figures 8 to 12, the valve 4 is provided with a casing 40 having a 100 cover 41, which is disposed preferably at the lower end of the tank 5. The port 42 in the casing 40 communicates on one side with the pipe 8 leading from the supply tank 3 and communicates on the other side with 105 the valve chamber 43 in which the operating parts of the valve are contained. At the upper end the chamber 43 is closed off by the wall 44 through which wall 44 the valve rod 45 projects. A stuffing box seals 110 the opening through which the piston rod 45 projects. The movable member for shifting the main air valve mechanism comprises a valve rod 45 having operable connection with the sleeve valve member 49 working 115 in the cylindrical passageway 46, which valve member 49 is connected to the piston 50 disposed in the cylinder 51. The cylinder 51 is open to the interior of the tank 5 and the upper surface of the piston 50 is 120 therefore subject to the pressure in said tank 5. The piston 50 lies between the passageway 46 and the tank 5 and is subject on opposite sides to the pressures prevailing in the passageway and in the tank. The port 47 communicates with the lower end of the passageway 46 and has connection with the water discharge pipe 12.

The interior of the cylindrical sleeve valve 49 communicates through the lower end 125 52 130

with the passageways 46—47. The ports 53 permit the water to flow into the lower confined portion of the cylinder 51, which is between the under side of the piston 50 and the passageway 46. This arrangement affords an effective pressure area on the under side of the piston 50 substantially equal to that of the top side of the piston 50. The under side of the piston 50 is subjected to the pressure of the water discharge line 12 and the top side of the piston is subjected to the pressure in the tank.

The side walls of the cylindrical valve member 49 are provided with ports 54 adapted to register with the passageways 55—56 which lead to the interior of the tank 5 by way of the common opening or passageway 59. This common passageway 59 is controlled by the float valve 58 which closes the passageway 59 when the predetermined low level is reached in the tank 5. The float valve 58 is preferably a rubber ball of what is known as floating stock. This valve is guided in the cage 130, which permits communication between the passageway 59 and the interior of the tank 5 through the ports 131 and 132.

The passageways 55 and 56 contain check valves 57 and 57' which permit movement of liquid in one direction only, the passageway 55 opening toward the tank 5 and the passageway 56 opening away from the tank 5. The piston valve 49 selects the proper passageway to register with the port 54 and in making such selection it shifts the motive fluid valve proper that controls admission and exhaust of the main pump chamber. The float valve 58 controls the application of pressure to the piston 50 for the purpose of shifting the sleeve or piston valve 49 and the main motive fluid valve. I have shown the piston rod 45 threaded into the sleeve valve 49, but it is apparent that any suitable connection may be employed.

The air control valve controlling the admission and exhaust of motive fluid to the pump cylinder 1, as shown in Figures 8, 9, 10, 11 and 12, comprises the movable valve members 60 and 61, the movement of which is caused by the valve rod 45 controlled by the piston 50. The valve member 60 has a motion with respect to the member 61, which latter has motion with respect to the seat 67. This relation is secured by providing the lower valve member 61 with a lower face seating on the valve seat 67 and with an upper face engaging the face of the valve member 60. The different degrees of movement of the two members is secured by connecting the upper member 60 directly to the valve stem 45 without lost motion and by connecting the lower valve member 61 to the stem by a lost motion connection. The stem 45 has the projections 70—71 between

which the lower valve 61 is located and by 65 which it is moved.

The valve seat 67 has three ports 64, 65 and 66, of which the port 64 opens to exhaust, port 65 communicates with the main pumping chamber as shown in Figure 1 (or 70 it may communicate with the motor cylinder of a relay valve structure such as shown at the left of Figure 3 and Figures 5 and 6) and the port 66 leads to the inside of the casing 40 which casing is under pressure of 75 the motive fluid supplied by way of pipe 8 and inlet 42.

The valve member 61 contains on its lower face a recess 133 adapted to communicate with the port 65 in all positions of the 80 valve member 61. A lateral branch from the recess 133 forms a port 66 which in one position is adapted to put the recess 133 into communication with the port 55. The valve member 61 also contains a passageway 134 85 adapted at the extreme upper position of the said valve member to communicate with the port 64 in the seat 67. This passageway 134 terminates in the upper side of the member 61. The recess 133 communicates 90 with the upper side of the member 61 by a short passageway 63, these passageways 63 and 134 terminating closely adjacent each other so that they can be controlled by the member 60, which forms a D slide valve 95 member having a recess 62 on its lower face.

The valve member 61 is seated between guiding flanges 68 and the valves are held in place for shipment and idle condition by a suitable spring 69.

The operation of the system as shown in Figure 1 and in the details of Figures 7 to 12 inclusive is as follows: Assuming that the main pumping chamber 1 is properly submerged in the liquid to be pumped as in 105 a suitable well or other suitable source of supply, the auxiliary pumping chamber being located above the liquid—preferably at the head of the well as shown in Figure 1—and the proper supply of air furnished as 110 by means of the compressor 6 and the storage tank 3, the operation of the system may be started by connecting the pipe 8 with the pipe 10 manually by means of a temporary valve connection (not shown) until the pipes 115 12 and the auxiliary pumping chamber 2 are properly filled with liquid. The air may be permitted to escape at one of the faucets while the system is filling with liquid. Several strokes of the main pumping chamber 1 may thus be made to charge the system with 120 liquid and thereafter the operation will be automatic. Air at reduced pressure is supplied to the top of the auxiliary pumping chamber 5, as previously indicated. Assuming that the main pumping chamber has 125 just completed a stroke by discharging water into the auxiliary chamber 5; the pis-

ton 50 with its attached valve 49, stem 45 and air valve members 60 and 61 will have been moved to the extreme upward position as shown in Figure 13 and also as illustrated 5 in the upper right hand corner of Figure 13. The water which is discharged from the main pumping chamber 1 will pass up through the pipe 11 through the pipe 12, passageways 47 and 46 to the interior of the 10 sleeve valve 49, through the port 54 and the passageway 55, past the check valve 57 which opens to permit this operation and upwardly through the common port 59 into the interior of the auxiliary pumping chamber 15 or air spring 5. This discharge of water into the auxiliary pumping chamber 5 raises the pressure of the air which is trapped in the top of the same. The further discharge of water is stopped by either the 20 equalization of pressure in the chambers 1 and 5 or by the float valve 35 dropping down and closing the port 34 so that no further discharge of water from the main pumping chamber 1 can occur. In either event the 25 system then stands stationary so long as no water is withdrawn from the system. If any water is now withdrawn from one of the faucets by opening of the same, water will be discharged either from the main 30 pumping chamber 1, if it had not previously been emptied, until the float valve 35 closes off the port 34. As soon as the float valve 35 has closed the port 34 and further water is permitted to escape from the system, 35 pressure in the pipe 12 and below the piston 50 will be lowered immediately. It will be seen that it is impossible for water to flow back from the auxiliary pumping chamber 5 to the passageway 55 because the check 40 valve 57 will not permit such action. The consequence is that as soon as the pressure lowers, due to the withdrawal of water after the main pumping chamber 1 is emptied, the pressure in the auxiliary pumping chamber 45 5 will force the piston 50 down until the ports 54 in the sleeve valve 49 come into register with the passageway 56, whereupon water will be discharged from the air spring to provide at the faucets for discharge. As 50 previously explained, during the time of discharge of the water from the main pumping chamber 1 the valve means 60 and 61 stands in the uppermost position as shown 55 in Figure 8. The motive fluid at this time entering by way of the opening 42, as shown in Figure 11, into the interior of the valve box 40, passes down through the passageway 63 through the passageway 65 and pipe 10 to the main pumping chamber 1.

60 As soon as the reversal of flow occurs as above indicated, that is, as soon as water flows from the auxiliary pumping chamber 5 to supply the discharge pressure at the faucet, the upper valve member 60 will be 65 shifted into the position shown in Figure 9.

This shifting of the D valve 60 connects the pump to exhaust by way of the passageway 65, recess 133, passageway 63, passageway 62, valve 60, passageway 134 and out the exhaust port 64 to atmosphere. 70

When the piston 50 moves downward to shift the valve 60 to permit exhaust of the main pumping chamber 1 the sleeve valve 49 is shifted to permit the water from the auxiliary pumping chamber 5 to flow into 75 the distribution system by way of the openings 61, port 60, passageway 56 past the check valve 57 through the ports 54, passageways 46 and 47 and out by way of the pipe 12. The piston 50 will, as above explained, move downward only until the port 54 is in register with the passageway 56 and this movement is just sufficient to shift the valve 60 to the exhaust position as above 80 explained. 85

The auxiliary pumping chamber 5 then continues to supply liquid to the distribution system until the liquid therein is lowered to a predetermined minimum, whereupon the float valve 58 will close the port 60. This 90 immediately creates a difference in pressure on the two sides of the piston 50 as the water escapes from the lower side thereof out by way of the discharge system. The piston 50 will thereupon move downward to its lowermost position, carrying the sleeve valve 49 downward so that the ports 54 are below the passageway 56 and carrying the valves 60 and 61 to the lowermost position, as shown in 95 Figure 10. It will be seen that movement of the valve member 61 first closes off the exhaust passageway 64 and thereafter connects the recess 133 in the valve member 61 by means of the lateral branch 66 with the passageway 66' so that motive fluid is admitted 100 from the interior of the valve box 40 through the passageway 66 in the valve seat 67 through a recess 133 to the passageway 65 which leads by way of pipe 10 to the main pumping chamber 1. This admission of air 105 to the main pumping chamber results in immediate discharge of liquid therefrom with the result that the liquid tends to force its way into the auxiliary pumping chamber 5 by way of the passageway 47-46 raising 110 the piston 50, the sleeve valve 49 and moving valves 60 and 61 to their uppermost positions. 115

The piston 50 is forced upwardly by the preponderance of fluid pressure on the lower 120 side thereof. This is due to the reversal of flow of the liquid as previously explained. As the sleeve valve 49 passes upwardly the ports 54 will first be brought into register with the passageway 56, but the check valve 125 57 prevents the discharge of liquid through said passageway and the sleeve valve is carried upwardly until the ports 54 register with the passageway 55, whereupon the liquid from the main pumping chamber 1 will 130

be discharged through the passageway 55 and port 59 into the auxiliary pumping chamber 5.

In the upward movement of the valve members 60 and 61 the first motion of the stem 45 moves the D valve 60 to uncover the port 63, thus permitting the motive fluid to enter and pass to the main pumping chamber 1. This movement of the valve member 60 5 first cuts off the exhaust passageway 64 before opening the admission passageway 63. Upon further movement of the rod 45 the valve member 61 is moved upwardly, disconnecting the recess 133 from the admission 10 passageway 66', but as motive fluid is permitted to enter the passageway 63 the supply of motive fluid is thus continuous from the time that the valve stem reaches its lowermost position to the time that it reaches its 15 uppermost position and is started back again.

The faucet may be opened and closed at any stage of the above operations without affecting the previously described cycle.

25 Figures 2 and 3 illustrate a system where the valve 4 operates through the operating element 75 to work the controlling valve 76. In this case the controlling element 75 consists of a small cylinder 77 communicating by way of the pipe 10 with the valve 4. The cylinder 77 is provided with a lining 78 that has a seat 79 at the upper end as will be explained later. A movable piston member 80 is adapted to slide into the cylinder 77. A 30 rod 81 is connected by means of a spring connection 82 with the piston 80 and extends down through the pipe 83 to the controlling valve body 84 which is preferably located adjacent the head of the pump 1.

40 The pipe 83 communicates by means of a T connection 85 with the pipe 86 which is connected in turn to the pipe 13 communicating with the compressed air tank 3. It can thus be seen that the piston 80 is subjected 45 on the one side to the pressure prevailing in the pipe 10 and on the other side to the pressure of the motive fluid admitted through the pipe 86. The piston 80 is provided at its upper surface with a valve seat 87 adapted to engage the seat 79 to prevent any leakage past the piston 80 when the piston is moved to its uppermost position.

50 The controlling valve 76 comprises a substantially cylindrical body provided with a transverse exhaust passage 87 and axial passageway 88, which communicates by way of the reduced portions 89 with the pipe 90 leading to the cylinder head 20, and the interior of the main pumping chamber 1. The portion 89 of the valve member 84 and the pipe 90 are joined together by a union which has a flared funnel shaped member 91, at its upper edge for directing the reduced parts 89 of the valve body 84 to the threaded part 65 of the union. By this means if any disar-

rangement of the valve within the valve body 84 should occur the same may be unthreaded at the union and raised to the surface. The reduced portion 89 may again be threaded into the union without difficulty because of the funnel shape guiding member 91 which directs it into the threaded portion. The funnel shaped member 91 is substantially of the same diameter as the pump 1 and embraces the water pipe 11, hence it is easy to 70 cause engagement of the screw threads.

The valve body 84 has a head member 92 provided with a port 93. A valve guiding member 94 passes through said port 93 and guides the valve body 95 in opening and closing said port. The valve guiding member 94 is connected to the rod 82 which, as previously explained, is connected to the piston 80. The valve member 95 comprises an outer shell having a yieldable face 96 at its upper surface. A screw plug 97 enters the bottom of the shell of the valve member 94 and embraces the cylindrical part 98, which has an annular shoulder 99 at its upper end. The cylindrical part 98 slides in the ring 97. A 90 yieldable valve face 100 co-operates with the exhaust port 101, which valve face 100 is secured to the cylindrical member 98. It can thus be seen that the cylindrical member 98 with its shoulder 99 forms a lost motion connection with the rod 81 to the various parts previously described.

The operation of the system shown in Figures 2 and 3 is substantially the same as that shown in Figure 1 with the exception that the motor 75 and valve 76 operate as a relay for controlling the admission and exhaust of motive fluid to and from the main pumping chamber 1. When the flow controlled valve moves to the position shown in Figure 10 to start the admission of air to the pipe 10, the piston 80 is moved downwardly in the cylinder, moving the rod 81 and the valve member 97 downwardly to open the port 93 which admits motive fluid to the main pumping chamber 1 and closing the port 101 to exhaust. The water then discharges from the main pumping chamber into the distributing system and into the auxiliary pumping chamber 5, the reversal of flow at this time causing the rise of the piston 50 and the connected sleeve valve 49 and the valve member 60 to the position shown in Figure 8. As soon as the water has been expelled from the main pumping chamber 1, the valve 35 closes off the port 34, the pressure drops in the discharge system sufficiently to permit the piston 50 and connected parts to drop down to the position where the valve 49 places the ports 54 in communication with the passageway 56 and connects the main pumping chamber to exhaust as shown in Figure 9, whereupon the auxiliary pumping chamber 5 provides the supply to the distributing 115 120 125 130 135

system until the float valve 58 closes off the port 60, whereupon the piston 50 is forced down to its lowermost position, moving the valve members 60 and 61 to the position shown in Figure 10 for the admission of motive fluid to the main pumping chamber.

When the valve member 60 is moved to the position shown in Figure 9, the pressure in the top of the cylinder 77 is exhausted to atmosphere, whereupon the pressure prevailing on the under side of the piston 80 forces the same upward, raising the rod 81 and taking up the lost motion between the member 95 and the stem 98, compressing the spring 82 and then pulling the valve member 97 from the exhaust port 101 and closing the admission valve 95 against the admission port 93. At the same time the yieldable seat 87 engages the metallic seat 79 to seal off the chamber 77 to prevent the escape of live air around the piston 80.

The relay mechanism 75-76 may be operated by liquid from the distributing system or from the auxiliary pumping chamber 5, the valve mechanism 4 being modified as shown in Figure 13 and as will be described in detail in connection with the embodiment shown in Figure 4.

In the system shown in Figure 4 the float controlled valve mechanism 4 operates through a relay mechanism comprising a motor and valve governing the admission and exhaust of motive fluid to and from the main pump chamber 1. In this system the motor and valve mechanism is combined in a simple, compact structure 106, adapted to be placed adjacent the main pumping chamber as shown in Figure 4. This motor and valve unit 106 comprises a diaphragm chamber 109 communicating by way of the pipe 105 with the passageway 65 shown in the valve seat of the valve mechanism 4 in Figures 8, 9, 10 and 11. The diaphragm chamber has a diaphragm 111 to which are clamped suitable diaphragm plates 110, the inner one of which has the yieldable face 119 adapted to co-operate with the exhaust port 118. The pipe 105 is constantly full of liquid and the weight of this liquid column pressing against the diaphragm 111 tends to force the valve 119 to the closed position. However, this tendency is balanced by means of a suitable spring 122 interposed between the lower diaphragm plate and the casing.

The body of the valve mechanism comprises a cylindrical member 115 having the exhaust port 118 and the admission port 116. The admission port 116 is controlled by the valve 117 and leads to an inlet member 112 connected by way of the pipe 108 and the pipe 86 to the pressure tank 3. The barrel or cylinder 115 has a central portion 114 which communicates with the main pumping chamber 1 by way of the pump connection

113 and pipe 90. The diaphragm plates 110 have connected to them the valve rod 120 provided with the guiding wings 121. Upon the rear end of the valve rod 120 is connected the admission valve 117. Thus when the valve member 4 is operated to admit pressure to the pipe 105, the diaphragm 111 is pushed downwardly as viewed in Figure 6, opening the admission valve 117 and admitting compressed air or other motive fluid to the main pumping chamber 1, causing the same to discharge liquid therefrom. The flow responsive mechanism of the valve member 4 is actuated as soon as the main pumping chamber 1 is emptied to exhaust the pressure in the pipe 105, permitting the spring 122 to move the diaphragm 111 upwardly as viewed in Figure 6, closing off the admission port and opening the exhaust port. Thereafter the main pumping chamber 1 fills and the auxiliary pumping chamber 5 supplies the discharge pressure until this auxiliary pumping chamber is emptied, whereupon the valve member 4 is again shifted to admit pressure to the diaphragm chamber 109 to close the exhaust port and open the admission port.

As previously explained, the pipe 105 is always full of liquid, consequently there is no wastage of compressed air or other motive fluid. The valve mechanism 4 in this form of the device is illustrated in Figure 13. In this case the interior of the valve box 43 is open to the passageway 46-47 so that the pressure of the liquid prevailing in the discharge system or pipe 12 is admitted to the valve chamber. This liquid pressure is employed to operate the relay device 106 above described. The operation of the valve mechanism shown in Figure 13 is identical with that described in connection with Figures 8, 9, 10, 11 and 12, with the exception that the motive fluid in this case is water under pressure instead of compressed air. Consequently the exhaust which occurs from the valve shown in Figure 13 is the discharge of a small amount of water which, of course, may be run through a suitable drain.

One particular advantage of employing a system of this type is the fact that under no conditions can the compressed air flow over due to a shortage of water in the well. Thus, if the water supply in the well should fail the float valve 35 shuts off the passageway 34 and as soon as the water is exhausted from the auxiliary pumping chamber 5 the float valve 58 shuts off the passageway 60 and no escape of air is possible.

The control of the air valve in accordance with the direction of flow is ideal in that it is not dependent upon the pressures and leakage of the parts consequently does not affect the control. Furthermore, the control, according to the flow, permits of greater economy in separate head pumps than any

other scheme of operation with which I am familiar. This is apparent when it is considered that filling of the auxiliary chamber 5 does not entail an immediate exhaust of the main pumping chamber 1. The main pumping chamber 1 invariably makes a full stroke before reversal occurs, and consequently the efficiency will be high. The provision of the float control valve 58 in the auxiliary pumping chamber also insures that this chamber will do the proper amount of work and it consequently gives a maximum amount of time for the filling of the main chamber 1. The valves will not center on dripping service because the piston member 50 and sleeve valve 49 must move a definite distance before water can be discharged from the system and this invariably opens the controlling ports of the valve mechanism 4 or closes them and the valves 60 and 61 are so arranged that the ports thereof are blanked during intermediate stages.

I now wish to call attention to the fact that the piston 50, together with the check valve passageways 55 and 56, constitute a flow meter device which is sensitive to direction of flow.

The passageway 55, for example, exerts a restrictive effect upon the liquid flowing therethrough to produce a difference in pressure upon opposite sides of the piston 50, the preponderance of pressure being then upon the lower side. But this alone would be merely a flow meter sensitive to rate of flow only. For my purposes, the device must be sensitive to change in direction of flow. I make the device responsive to change in direction of flow by blocking off all flow through the sleeve valve 49 until the main air valve 43 is shifted, that is, until the sleeve valve 49 opens the port or passageway 55. Thereafter, the variable rate of flow exerts a variable difference of pressure upon the piston 50, but that is unimportant so long as the preponderance is all in one direction.

As soon as it is necessary for the water to flow out of the air spring to supply the demand of the system, the flow tends to reverse through the common connection 12. But outflow is blocked by check valve 57 and sleeve valve 49. Hence, the difference in pressure which tends to set up flow out of the air spring 5 exerts a great enough difference in pressure upon the piston 50 to push said piston 50 and sleeve valve 49 together with main control valve 43 downwardly, and as long as there is an outflow from the air spring 5 the preponderance of pressure is maintained on top of the piston 50.

Thus it will be seen that I have provided a flow meter device sensitive to reversals of flow; this device comprising an orifice and a pressure responsive device subjected to differences in pressure, which tend to set up flow.

I do not intend to be limited to the precise details of construction shown or described. I claim:

1. In combination, a distribution system, a main pumping chamber and an auxiliary pumping chamber connected to said distribution system, means responsive to the flow of liquid from one of said chambers to said distribution system and a valve for motive fluid controlled by said means governing the exhaust of motive fluid from the other of said pumping chambers.

2. In combination, a normally closed distribution system, a pair of pumping chambers connected to said system, one of said chambers being submerged in the liquid to be pumped the other of said chambers being above the liquid, means responsive to the flow of liquid from the other of said chambers to the system for governing the exhaust of motive fluid from one of said pumping chambers.

3. In combination, a closed distribution system, a pair of pumping chambers, one of said chambers only being submerged in the liquid to be pumped, said system and said chambers having a common junction point, valve means for controlling the admission and exhaust of motive fluid to and from one of said chambers, and means responsive to change in flow of liquid at said junction point for shifting said valve, said means moving with flow until the valve is shifted.

4. In a system of the class described, a main pumping chamber adapted to be submerged in the liquid, an auxiliary pumping chamber above the liquid, a passageway connecting said chambers, a normally closed discharge system communicating with said passageway, means for supplying motive fluid to the main pumping chamber, and means controlled by the change of flow of liquid in said passageway governing the exhaust of motive fluid from said main pumping chamber.

5. In combination, a main pumping chamber adapted to be submerged in the liquid to be pumped, an auxiliary pumping chamber adapted to receive liquid from the main pumping chamber and to discharge the same during filling strokes of the main pumping chamber, a discharge pipe having connection with both of said chambers, and valve means controlled by emptying of the main pumping chamber to connect said main pumping chamber to exhaust, and controlled by emptying of the auxiliary pumping chamber to admit motive fluid to the main pumping chamber.

6. In combination, a pump cylinder having liquid inlet and discharge valves, a discharge pipe, a pipe for conveying motive fluid to the pump, an auxiliary pumping device, a valve controlled by the change in direction of flow of liquid into and out of the

- auxiliary pumping device independently of the amount of liquid content thereof.
7. In combination, a pump cylinder having liquid inlet and discharge valves, a discharge pipe, a pipe for admitting and exhausting motive fluid to and from the pump, an accumulating chamber, a device actuated by the change of direction of flow of liquid to and from said chamber independently of the amount of liquid therein, a valve having connection with said device controlling the admission and exhaust of motive fluid to and from the pump.
8. In combination, a pump cylinder having inlet and discharge valves, a discharge pipe, a motive fluid pipe, a valve governing the flow of motive fluid in said pipe, an auxiliary pumping device having an accumulating chamber and a movable stroke responsive element, said stroke responsive element being controlled by the change of direction of flow of water to and from the accumulating chamber independently of the contents thereof, a valve operated by the movement of the stroke responsive element controlling the operation of the pump.
9. In combination, a pump adapted to be submerged in water at the foot of the well, a water discharge pipe, a motive fluid pipe leading from the pump, a motive fluid valve, an air spring adapted to accumulate water upon each stroke of the pump, a control valve having a motor element moved by differences of pressures in the air spring and discharge pipe, the movement of the motor element being governed by the flow of water in the air spring.
10. In combination, a pump cylinder adapted to be submerged in water at the foot of the well, a discharge pipe leading from said well and communicating with an auxiliary pumping device, a motive fluid pipe, a valve at the foot of the well adjacent the pump cylinder, a master valve governed by the reversal of the flow of the water to or from the auxiliary pumping device independently of the contents thereof, an operating element at the head of the well controlled by said master valve for admitting and exhausting motive fluid to and from said motive fluid pipe.
11. In combination, a pump cylinder adapted to be submerged in water at the foot of a well, a discharge pipe leading from said cylinder and communicating with an accumulating chamber, piston means governed by the flow of water from said chamber controlling a master valve connected therewith, a valve at the foot of the well adjacent the pump, an operating element, a source of motive fluid, said master valve adapted to exhaust water under pressure from said controlling element to cause the valve at the foot of the well to exhaust motive fluid from said pump.
12. In combination, a pump cylinder adapted to be submerged in water at the foot of a well, a discharge pipe leading from said well, an air pipe, a controlling valve governing the air pipe comprising admission and exhaust valves, a lost motion connection between said valves, means supplying air under pressure to said valves, an operating piston at the head of the well controlling said valves, one side of said piston being subjected to the pressure of water in said discharge pipe.
13. In combination, a pump cylinder having a liquid discharge pipe, a motive fluid pipe, a check valve for said discharge pipe and a float valve in the pump cylinder, a main valve governing the flow of motive fluid in said pipe, said float valve adapted to seat when the liquid in the cylinder reaches a predetermined level to prevent further displacement of liquid from said pump cylinder, and means controlled by the drop in pressure created in the discharge pipe for governing the operation of said main valve.
14. In combination, a pump, adapted to be submerged in a well, a water discharge pipe, a steady flow chamber, a stroke responsive element communicating with the water discharge pipe and with the chamber, a valve member having connection with the stroke responsive element shifted by the movement of said element, said stroke responsive element being moved when the pressure in the discharge pipe lowers.
15. In combination, a discharge pipe, an accumulating chamber having a reciprocable piston, said piston communicating on one side with said chamber and on the other side with said distributing pipe, means for causing the piston to be forced outward, a pump discharging water into the chamber and moving the piston inward and a valve operated by the movement of the piston, said valve governing the operation of the pump.
16. In combination, a discharge pipe, an auxiliary pumping device having an accumulating chamber connected to said pipe and a reciprocable pressure piston one side of which communicates with the interior of the accumulating chamber, a pump discharging water against the other side of said piston and into said chamber, said device being adapted to discharge the water upon lowering of the pressure in the discharge pipe and a valve operated upon the reversal of the flow of water governing the operation of the pump.
17. In combination, a distribution system, a main pumping chamber, an auxiliary pumping chamber, a connection between said chambers, a movable member lying in said connection and subjected to the difference in pressure which results in changing the direction of flow of the liquid, a valve governing

- the flow of liquid around said movable member, and a main valve governed by the operation of said movable member for controlling the application of motive fluid to the main pumping chamber.
18. In combination, a normally closed delivery system, an auxiliary pumping chamber, a main pumping device connected to said system and said chamber, means controlled by the flow of liquid to or from the auxiliary pumping chamber independently of the contents of said chamber for controlling the operation of the main pumping device.
19. In combination, an air displacement pump, a pressure system connected thereto, an air spring, a connection between the air spring and the system comprising a bore open at one end into the air spring and at the other into the pressure system, a piston slidably in said bore, said piston being moved upon the initiation of a change of flow between the system and the air spring, and an air valve for the pump actuated by the piston.
20. In combination, a pressure system, a pump, an air spring, a connection between the pump and the air spring, a pressure operated element subject to the pressure of the liquid in the air spring in one direction and to the pressure of the liquid in the connection in the other direction, a valve governing the creation of differences in pressure in the air spring and in the connection, and a main valve operated by said element governing the operation of the pump.
21. In combination, a distribution system, a pump, an air spring, a connection between the pump, the air spring and the system, a movable element in the connection exposed on one side to the liquid in the system and on the other side to the pressure in the air spring, said pump being adapted to discharge water to the system and to the air spring, and a controlling valve for the pump governed by the movable element.
22. In combination, a delivery system, a pump, an air spring, a movable element in the connection between the pump and the air spring, means for causing the movement of the element in one direction when the pump discharges into the air spring, means for causing the movement of the element in the reverse direction when the liquid flows out of the air spring at the end of the pump stroke, means for causing further movement of the element in said reverse direction, when the liquid in the air spring has reached a predetermined low level, and a main valve operated by said movable element governing the operation of the pump.
23. In combination, a pressure delivery system, a main pumping chamber, an auxiliary pumping chamber, a connection between the main pumping chamber and the auxiliary pumping chamber, said connection communicating with the system, a motive fluid control valve for the main pumping chamber, a movable element in the connection between the main pumping chamber and the auxiliary pumping chamber, a pair of by-passes comprising check valve passageways adapted to be obstructed by said movable element to create differences of pressure on opposite sides of the movable element, a low level float in the main pumping chamber for creating a difference of pressure on said movable element and a low level float in said auxiliary pumping chamber for creating a difference of pressure on said element.
24. In combination, a pump, an air spring, a distribution system connected to the pump and to the air spring, a motive fluid control valve adjacent the pump for controlling admission and exhaust of motive fluid to and from the pump, a motor element for said main valve, a movable element controlled by the emptying of the air spring for applying liquid under pressure from the air spring to said motor element for operating the main valve.
25. In combination, a main pumping chamber, an auxiliary pumping chamber, a connection between them, a closed delivery system communicating with said connection, a motive fluid valve for the main pumping chamber, a low level float for shutting off the discharge of liquid from the main pumping chamber and a flow responsive means governed by flow of liquid from the air spring into the system for operating said main valve to connect the main pumping chamber to exhaust.
26. In combination, a main pumping chamber, an auxiliary pumping chamber, a connection between said chambers, a delivery system communicating with said connection, a main motive fluid valve governing the main pumping chamber, a movable element subject to difference in pressure between the discharge side of the main pumping chamber and the pressure in the auxiliary pumping chamber for operating said main valve to connect the main pumping chamber to exhaust.
27. In combination, a main pumping chamber, an auxiliary pumping chamber, a connection between said chambers, a closed distribution system communicating with said connection, a low level float valve for shutting off the discharge of liquid from the main pumping chamber, a low level valve for shutting off the discharge from the auxiliary pumping chamber and a main motive fluid valve for the main pumping chamber controlled by said low level valve.
28. In a pumping system, the combination of a pumping chamber adapted to be filled with liquid and then emptied of liquid.

uid by air displacement, valve means controlling the movement of air into and out of the pumping chambers and means controlled by cessation of flow of liquid from the pumping chamber for shifting said valve means.

29. In a pumping system, a pumping chamber adapted to be filled alternately with liquid and with motive fluid, a main valve 10 for motive fluid and means controlled at each stroke by cessation of fluid flow from the pumping chamber for shifting the main valve.

30. In combination, a pumping chamber, 15 an air spring, a normally closed distributing system connected to said air spring and said pumping chamber, an air valve for admitting and exhausting air to and from the pumping chamber, flow responsive means 20 actuated by change in direction of flow of liquid in the connection between the air spring and the system independently of the amount of liquid contained in the air spring for operating said air valve.

31. In combination, a pumping chamber, an air spring, a normally closed distributing system connected to said air spring and to said pumping chamber, an air valve for admitting and exhausting air to and from 30 the pumping chamber, and flow responsive means for actuating said air valve, said flow responsive means cutting off said air spring from the pumping chamber and the distributing system upon the cessation of a discharge stroke of the pumping chamber.

32. In combination, a pumping chamber, an air spring, a normally closed system connected to said air spring and said pumping chamber, an air valve for admitting and 40 exhausting air to and from the pumping chamber to make the pumping stroke, a common junction point between the air spring, the system and the pumping chamber, check valves between the air spring and said common junction point, and means for disabling said check valves one at a time, said means being connected to said air valve.

33. In combination, a pump, an air control valve therefor, an air spring, a discharge pipe from the pump to the air spring,

a distributing pipe leading from the air spring and communicating with said discharge pipe, and means actuated to shift the air valve to exhaust position as soon as the rate of flow from the distributing pipe exceeds the rate of flow from the discharge pipe.

34. In combination, a pump, an air control valve therefor, an air spring, a discharge pipe from the pump of the air spring, 60 a distributing pipe leading from the air spring and communicating with the said discharge pipe, and flow responsive means to shift said air control valve to exhaust position when the rate of flow from the distributing pipe exceeds the rate of flow from the discharge pipe and means governed by emptying of the air spring for shifting the air control valve to admission position.

35. In a pneumatic displacement pump, a 70 pumping chamber, a main air control valve therefor, a distributing pipe, an air spring, a common passageway connecting the air spring with the pumping chamber and the distributing pipe, and a flow meter device 75 sensitive to change in direction of flow in said common passageway for controlling said air control valve.

36. In a pneumatic displacement pump, a pumping chamber, a main air control valve, 80 a distributing pipe, an air spring connected by a common passageway to the pumping chamber and to the distributing pipe, and a flow meter device sensitive to change in direction of flow in said common passageway 85 for controlling said air control valve to make the strokes of the pumping chamber, said device comprising a movable piston member sensitive to fluid pressures at different points in said passageway, a valve means connected 90 to the member for blocking the passageway until the piston member is moved, and a connection from the member to the main valve for shifting the main valve when said piston member moves the valve means to uncover 95 the fluid passageway.

In witness whereof, I hereunto subscribe my name this 7th day of September, 1921.

BURTON S. AIKMAN.

Certificate of Correction.

It is hereby certified that in Letters Patent No. 1,600,385, granted September 21, 1926, upon the application of Burton S. Aikman, of Milwaukee, Wisconsin, for an improvement in "Pumping Systems," an error appears in the printed specification requiring correction as follows: Page 11, line 60, claim 34, for the word "of" read *to*; and that the said Letters Patent should be read with this correction therein that the same may conform to the record of the case in the Patent Office.

Signed and sealed this 9th day of November, A. D. 1926.

[SEAL.]

WM. A. KINNAN,
Acting Commissioner of Patents.
